Notice of Allowance dated Apr. 15, 2021 from the US Trademark & Patent Office in U.S. Appl. No. 35/509,104.

Primary Examiner — Mary Ann Calabrese*(74) Attorney, Agent, or Firm* — Sughrue Mion, PLLC(57) **CLAIM**

The ornamental design for a mattress, as shown and described.

DESCRIPTION

1. Mattress

1.1 : Bottom perspective view

1.2 : Front

1.3 : Back

1.4 : Top

1.5 : Bottom

1.6 : Left

1.7 : Right

1.8 : Partial enlarged bottom view

1.9 : Sectional view

1.10 : Sectional view

The even dash broken lines show portions of the mattress that form no part of the claimed design. The long-dash, short-dash broken lines represent the boundaries of the claim and form no part thereof.

Reproduction 1.9 is an enlarged cross-sectional view taken along the center of reproduction 1.8. Reproduction 1.10 is an

(Continued)

enlarged cross-sectional view a little bit above the center of reproduction 1.8 at the claimed four circular holes.

1 Claim, 10 Drawing Sheets
